UNITED STATES PATENT OFFICE

GEORGE H. GILMAN, OF BELMONT, MASSACHUSETTS, ASSIGNOR, BY MESNE ASSIGNMENTS, TO WORTHINGTON PUMP AND MACHINERY CORPORATION, OF NEW YORK, N. Y., A CORPORATION OF VIRGINIA

DRILLING MACHINE

Original application filed June 5, 1920, Serial No. 386,868. Divided and this application filed June 4, 1926.
Serial No. 113,672.

This application is a division of my prior application Serial No. 386,868, filed June 5, 1920, on which Letters Patent of the United States No. 1,588,407 was issued June 15, 1926.

My invention relates to fluid pressure motors, and particularly but not exclusively to a hammer rock drill.

The invention will be best understood from the following description when read in connection with the accompanying drawings of an example of the invention, while the scope of the invention will be more particularly pointed out in the appended claims.

In the drawings:

Fig. 1 shows from the most part in longitudinal section a rock drill embodying the invention;

Fig. 2 is a fragmentary section on the line 2—2 of Fig. 1;

Fig. 3 is a section similar to Fig. 2 with the valves omitted;

Fig. 4 is a section on the line 4—4 of Fig. 1;

Fig. 5 is a section on the line 5—5 of Fig. 1;

Fig. 6 is a section on the line 6—6 of Fig. 1;

Fig. 7 is a section on the line 7—7 of Fig. 1;

Fig. 8 is a section on the line 8—8 of Fig. 1; and

Fig. 9 shows in perspective on an enlarged scale a portion of the mechanism for holding the water tube in position.

As illustrated, the drilling machine comprises a casing having a cylinder member 1 and a front head structure 2. Mounted for reciprocation in the cylinder is a piston 3 provided with a hammer bar 4 extending into the front head structure and adapted to operate by impact on the polygonal end 5 of the drill steel 6, the end of the steel being received in a polygonal recess in the chuck 7, the latter being mounted for rotation in the front head structure. In addition to being operated by impact the steel preferably is rotated by the piston, suitable mechanism being provided for this purpose, which will now be described.

As illustrated, the rear head structure comprises a block 8 in which is mounted a pair of ratchet wheels 9 and 10 respectively carrying the telescopically arranged rifle bars 11

and 12 which extend into the cylinder and piston and respectively engage the rifle nuts 13 and 14 carried by the piston. Formed on the exterior of the rifle bar 11 are grooves 15 which cooperate with lugs 16 on the rifle nut 13, while formed on the exterior of the rifle bar 12 are grooves 17 which cooperate with lugs 18 on the rifle nut 14. The hammer bar 4 extends into and is surrounded by the chuck, being connected thereto by grooves 19 formed on the hammer bar and cooperating with lugs 20 carried by the chuck.

Preferably the grooves 15 and 17 formed on the respective rifle bars have the same pitch and are oppositely inclined, while the grooves 19 formed on the hammer bar are parallel to the axis of the piston. The ratchet wheels 9 and 10 cooperate with suitable pawls 21 held in engagement therewith by spring pressed detents 22, the ratchet wheels and pawls being so arranged that both rifle bars may rotate in the same direction, rotation in the opposite direction being prevented by the pawls.

When the piston is reciprocated it is rotated on its rearward stroke by the rifle bar 12 in the direction indicated by the arrows in Fig. 1, and on its forward stroke it is rotated in the same direction by the rifle bar 11. When the piston rotates it rotates the chuck, and if the pitch of the grooves 15 and 17 is the same the chuck is rotated during each stroke of the piston in the same direction and through the same angle.

As illustrated, for controlling the reciprocation of the piston a valve 23 is provided, the valve being tubular so as to provide a conduit 24 opening through opposite ends of the valve. Herein the casing for the machine carrying the piston and valve is provided with parallel bores, in one of which the piston reciprocates and in the other of which the valve reciprocates.

The bore for the valve and the bore for the piston are connected near opposite ends of the bore for the valve by passages 25 and 26. Leading from the rearward end of the bore for the valve is a motive fluid supply conduit 27 in permanent communication with the internal conduit 24 of the valve. When the

valve is in the position shown by Fig. 1 the motive fluid passes from the interior of the valve and enters the passage 26 so as to operate upon the front end of the piston to drive it rearward, and when the valve is in its opposite position illustrated by Fig. 2 the passage 26 is cut off from communication with the interior of the valve, motive fluid then entering the passage 25 to act upon the rear end of the piston to drive the latter forward.

As illustrated, for exhausting the motive fluid admitted to the cylinder the valve is formed adjacent its ends with exterior grooves 28 and 29 with which respectively 15 cooperates grooves 30 and 30' formed in the interior wall of the valve casing. The grooves 30 and 30' are maintained in constant communication with the atmosphere by conduits 31 placed in communication with the 20 grooves by slots 32 and 33 respectively formed in the valve casing sleeves and body of the main cylinder portion. When the valve is in the position illustrated by Fig. 1 the groove 28 of the valve connects the passage 25 with the groove 30 and thus exhausts the rear end of the cylinder, and when the valve is in its opposite position illustrated by Fig. 2 the groove 29 connects the passage 26 with the groove 30' and thus exhausts the 25 forward end of the cylinder.

For providing additional exhaust means the central portion of the cylinder is provided with radial passages 35 which communicate with the passages 31. The passages 35 are arranged to be uncovered by the piston as it approaches the end of its stroke so as to permit the motive fluid moving the piston to exhaust to the atmosphere.

Herein the valve is provided with an enlarged portion 36 providing oppositely facing annular surfaces 37 and 38 on the exterior of the valve. In the present example of the invention the rearward end of the portion of the valve casing receiving the enlarged portion 36 of the valve communicates with the cylinder through a kicker passage 42 which opens into the cylinder through a port 39, while the forward end of this portion communicates with the cylinder through a kicker passage 41 which opens into the cylinder through a port 40. As the piston reciprocates it alternately covers and uncovers the ports 39 and 40 of the kicker passages, and thus alternately admits and exhausts motive fluid to and from the portion of the valve casing receiving the enlarged portion 36 of the valve for acting alternately upon the opposed surfaces 37 and 38 to cause the valve to reciprocate.

The valve is shown as formed with oppositely facing exterior annular surfaces 43 and 44, preferably of smaller area than the surfaces 37 and 38 and respectively facing in the same direction as the latter and being located between them and the corresponding

ends of the valve. The surfaces 43 and 44 of the valve face the annular surfaces provided by the shoulders between the different diameter portions 53 and 54 (Fig. 3) of the valve casing, and by this construction annular expandable chambers surrounding the valve are formed, each chamber having a working pressure surface on the valve and an opposed working pressure surface on the valve casing. The valve is shown as provided with radial passages 45 and 46 (Fig. 2) establishing communication between the interior conduit of the valve and its exterior. When the valve is in the position shown by Fig. 2 the passage 46 is closed by the portion of the valve casing fitting the exterior surface of the valve immediately forward of the surface 44, while the passage 45 may conduct motive fluid from the interior of the valve to its exterior to act upon the surface 43 so as to lock the valve in the position shown by Fig. 2. When the valve moves to the end of its travel opposite that indicated by Fig. 2 the passage 45 will be closed by the portion of the valve casing fitting the exterior surface of the valve immediately rearward of the surface 43, while the passage 46 may conduct motive fluid from the interior of the valve to its exterior to act upon the surface 44 so as to lock the valve in its rearward position.

For exhausting the motive fluid acting upon the surfaces 43 and 44 the valve casing is provided with passages 47 and 48 for respectively establishing communication between the portions of the valve casing adjacent the surfaces 43 and 44 and the exhaust grooves 30 and 30'. The rearward end of the passage 47 and the forward end of the passage 48 terminate on the exterior surface of the valve casing between the grooves 49 and 30 and the grooves 56 and 30'. Thus when the valve is in the position shown by Fig. 1 the passage 47 is in communication with the exhaust groove 30 and the passage 48 is closed from communication with the exhaust groove 30', while when the valve is at the opposite end of the travel the passage 48 is in communication with the exhaust groove 30' and the passage 47 is closed from communication with the exhaust groove 30.

As illustrated, the valve casing is formed of two telescopically arranged sleeves 50 and 51 held in assembled relation by a spring 52 which at one of its ends abuts a shoulder 54 formed on the inner sleeve 51 and at its other end abuts the block 8. The valve casing thus formed is provided on its interior surface with the annular grooves 49 and 56 respectively connected through the passages 25 and 26 to the cylinder and with the grooves 53, 54^a and 55 respectively forming chambers for the enlarged portions of the valve forming the surfaces 37, 38 and 43, 44.

The operation of the valve and piston is as follows: With the parts in the position shown

by Fig. 1 the motive fluid flows from the rear end to the forward end of the valve through its internal bore 24 into the groove 56 of the valve casing and hence into the forward portion of the cylinder by way of the passage 26, thus forcing the piston rearward. During the rearward stroke of the piston the motive fluid exhausts through the port 35 into the conduits 31 and discharges to the atmosphere, and also exhausts through the passage 25 around the reduced portion 28 of the valve into the groove 30 whence it flows through the slots 32 and 33 into the passage 31 leading to the atmosphere. In the position of the valve shown by Fig. 1 the space adjacent the surface 43 is exhausted by the passage 47 then connected to the atmosphere, while motive fluid is admitted to act against the surface 44 through the passage 46 which in this position of the valve is open. When the piston on its rearward stroke uncovers the port 39 of the kicker passage 42 motive fluid is admitted from the cylinder by way of the passage 42 to act on the surface 37 of the valve to throw it forward. As the valve moves forward the passage 46 is closed, and immediately after this the forward end of the passage 48 is opened to exhaust the motive fluid from the surface 44, while communication of the rearward end of the passage 47 with the exhaust is interrupted and the passage 45 is opened to admit motive fluid to act upon the surface 43. The valve is thus moved to and held in the position shown by Fig. 2. In the position shown by Fig. 2 motive fluid is admitted to the rearward end of the cylinder through the passage 25 and exhausted from the front end by the passage 26 and exhaust passage 35, which causes the piston to move forward. When the piston on its forward stroke uncovers the port 40 of the kicker passage 41 motive fluid is admitted to act upon the surface 38 of the valve and throw it rearward. The rearward movement of the valve closes the port 48 leading from the surface 44, and opens the port 46 which admits fluid to act upon the surface 44 to hold the valve in its rearward position.

The block 8 hereinbefore referred to is shown as provided with a transverse bore 60 receiving a manually operated throttle valve 61, the end of the bore being adapted to be connected with the source of motive fluid for supplying motive fluid for operating the machine.

Through the valve 61 is formed a longitudinal passage 62 having a transverse passage 63 communicating therewith, the latter being adapted to connect in the position of the valve shown by Figs. 1 and 2 with the passage 27 in the valve casing. The exhaust passages 31 in the valve casing communicate with the bore 60 through ports 64 which in the position of the valve shown by Figs. 1 and 2 are in communication with the atmosphere by way of passages 65 formed in the valve and communicating passages 66 formed in the head block. In the same transverse plane with respect to the valve as the ports 64 are passages 67 formed in the valve and communicating with the live motive fluid passage 62. If the valve is turned counterclockwise, as viewed in Fig. 1, the passages 65 are moved out of communication with the ports 64 and the passages 67 are placed in communication with said ports. This prevents operation of the machine because the exhaust is virtually closed, and the motive fluid now admitted to the exhaust passages 31 flows through passages 68 connecting the passages 31 with the rearward end of the chuck chamber 69. Motive fluid thus admitted to the rearward end of the chuck chamber passes to the forward end thereof by way of the grooves 19 formed on the exterior surfaces of the hammer bar and the space between the hammer bar and chuck. From the forward end of the chamber the motive fluid passes into the bore 70 of the drill steel and flows to the cutting end thereof to sludge the hole.

For supplying water to the hollow drill steel a tube 71 is shown which is supported in the base of the handle member 73 and extends through the machine to the front end thereof where it enters the bore of the steel. Communicating by means of a passage 82 with a chamber 75 formed in the handle member is a water supply connection 74. Herein the tube is supported by a member having a base portion 76 and a conical sleeve portion 77. The sleeve member is split or slotted as indicated at 79 and is cut away adjacent its juncture with the base 76 to form an annular groove 78. The slots 79 and grooves 78 render the sleeve portion flexible. In screw threaded engagement with the chamber 78 is a plug 80 provided with a conical recess 81 the taper of which corresponds to the taper of the conical sleeve 77. When the plug 80 is screwed into position the conical recess thereof clamps the sleeve against the tube 71 and holds the latter firmly in position. The base portion 76 is adapted to be forced by the plug 80 against the packing 82 to compress the same and form a tight joint about the tube to prevent entrance of water into the cylinder chamber. The water admitted to the chamber 80 finds its way through the slots 79 into the rear end of the recess 81 of the plug whence it passes into the bore of the tube 71 and finds its way into the hollow drill steel.

Although I have described one example of my invention it is to be understood that I am not limited thereto and that wide deviations may be made without departing from the spirit of the invention.

Claims:

1. A hammer rock drill having, in combination, a casing provided with parallel bores, a reciprocatory piston having opposed

working pressure surfaces in one of said bores, a reciprocatory tubular valve in the other of said bores, said valve having open ends in fluid communication with each other by way of the interior of said valve, a passage connecting a source of pressure fluid to the bore for said valve, said passage being in permanent communication with the interior of said valve through one open end of the latter, said valve provided with separate exterior annular surfaces facing in the same direction, means including a pressure fluid conducting passage leading from one of said bores to the other for creating a pressure condition on one of said annular surfaces in response to motion of said piston for causing said valve to move and to admit pressure fluid from the bore for the valve to the bore for the piston for acting upon one of said opposed pressure surfaces, said means also causing pressure fluid to act upon the other of said annular surfaces when the valve is so moved.

2. A hammer rock drill having, in combination, a casing provided with parallel bores, a reciprocatory piston having opposed working pressure surfaces in one of said bores, a reciprocatory tubular valve in the other of said bores, said valve having open ends in fluid communication with each other by way of the interior of said valve, a passage connecting a source of pressure fluid to the bore for said valve, said passage being in permanent communication with the interior of said valve through one open end of the latter, said valve provided with separate exterior annular surfaces, one of said surfaces being intermediate the length of said valve and both surfaces facing in the same direction, means including a pressure fluid conducting passage leading from one of said bores to the other for creating a pressure condition on one of said annular surfaces in response to motion of said piston for causing said valve to move and to admit pressure fluid from the bore for the valve to the bore for the piston for acting upon one of said opposed pressure surfaces, said means also causing pressure fluid to act upon the other of said annular surfaces when the valve is so moved.

3. A hammer rock drill having, in combination, a casing provided with parallel bores, a reciprocatory piston having opposed working pressure surfaces in one of said bores, a reciprocably tubular valve in the other of said bores, said valve having open ends in fluid communication with each other by way of the interior of said valve, a passage connecting a source of pressure fluid to the bore for said valve, said passage being in permanent communication with the interior of said valve through one open end of the latter, said valve provided with separate exterior annular surfaces intermediate its ends

facing in the same direction, means including a pressure fluid conducting passage leading from one of said bores to the other for creating a pressure condition on one of said annular surfaces in response to motion of said piston for causing said valve to move and to admit pressure fluid from the bore for the valve to the bore for the piston for acting upon one of said opposed pressure surfaces, said means also causing pressure fluid to act upon the other of said annular surfaces when the valve is so moved.

4. A hammer rock drill having, in combination, a casing provided with parallel bores, a reciprocatory piston having opposed working pressure surfaces in one of said bores, a reciprocatory tubular valve in the other of said bores, said valve having open ends in fluid communication with each other by way of the interior of said valve, a passage connecting a source of pressure fluid to the bore for said valve, said passage being in permanent communication with the interior of said valve through one open end of the latter, said valve provided with two pairs of oppositely facing exterior annular surfaces, the surfaces of each pair facing in the same direction and one surface of each pair being intermediate the ends of the valve, means including pressure fluid conducting passages leading from one of said bores to the other for creating pressure conditions on one surface of each pair of said surfaces in response to motion of said piston for causing said valve alternately to move to opposite ends of its travel and admit pressure fluid from the bore for said valve to the bore for said piston for acting alternately upon the respective surfaces of said opposed working surface of said piston, said means also causing pressure fluid to act alternately upon the other pressure surfaces of said valve when said valve is at opposite ends of its travel.

5. A hammer rock drill having, in combination, a casing provided with parallel bores, a reciprocatory piston having opposed working pressure surfaces in one of said bores, a reciprocatory tubular valve in the other of said bores, said valve having open ends in fluid communication with each other by way of the interior of said valve, a passage connecting a source of pressure fluid to the bore for said valve, said passage being in permanent communication with the interior of said valve through one open end of the latter, said valve provided with two pairs of oppositely facing exterior annular surfaces, the surfaces of each pair facing in the same direction and both pairs of surfaces being intermediate the ends of the valve, means including pressure fluid conducting passages leading from one of said bores to the other for creating pressure conditions on one surface of each pair of said surfaces in response to motion

of said piston for causing said valve alternately to move to opposite ends of its travel and admit pressure fluid from the bore for said valve to the bore for said piston for acting alternately upon the respective surfaces of said opposed working surface of said piston, said means also causing pressure fluid to act alternately upon the other pressure surfaces of said valve when said valve is at opposite ends of its travel.

6. In a fluid pressure motor, a cylinder, a piston therein, a valve having an internal conduit, admission and exhaust connections for said cylinder, the admission connection comprising said internal conduit, said valve having means to control said connections and being provided with separate surfaces facing in the same direction, means for creating a pressure condition on one of said surfaces to move said valve, and means for creating a pressure condition on the other of said surfaces to lock said valve when so moved.

7. In a fluid pressure motor, a cylinder, a piston therein, a valve having an open ended internal conduit, admission and exhaust connections for said cylinder, the admission connection comprising said internal conduit, said valve having means to control said connections and being provided with separate surfaces facing in the same direction, means for creating a pressure condition on one of said surfaces to move said valve, and means for creating a pressure condition on the other of said surfaces to lock said valve when so moved.

8. In a fluid pressure motor, a cylinder, a piston therein, a valve having an internal conduit, admission and exhaust connections for said cylinder, the admission connection comprising said internal conduit, said valve having means to control said connections and being provided with separate surfaces facing in the same direction, means responsive to motion of said piston for creating a pressure condition on one of said surfaces to move said valve, and means for creating a pressure condition on the other of said surfaces to lock said valve when so moved.

9. In a fluid pressure motor, a cylinder, a piston therein, a valve having an internal conduit, admission and exhaust connections for said cylinder, the admission connection comprising said internal conduit, said valve having means to control said connections and being provided with separate surfaces facing in the same direction, means responsive to motion of said piston for creating a pressure condition on one of said surfaces to move said valve, and means responsive to motion of said valve for creating a pressure condition on the other of said surfaces to lock said valve when so moved.

10. In a fluid pressure motor, a cylinder, a piston therein, a valve having an open ended internal conduit, admission and exhaust con-

nections for said cylinder, the admission connection comprising said internal conduit, said valve having means to control said connections and being provided with separate surfaces facing in the same direction, means for creating a pressure condition on one of said surfaces to move said valve, and means responsive to motion of said valve for creating a pressure condition on the other of said surfaces to lock said valve when so moved.

11. In a fluid pressure motor, a cylinder, a piston therein, a valve having an open ended internal conduit and being provided with exterior grooves and independent surfaces facing in the same direction, inlet and exhaust connections for said cylinder for supplying and exhausting the motive fluid for oppositely facing piston surfaces, the admission connection comprising said internal conduit and the exhaust connection comprising said grooves, means responsive to motion of said piston for creating a pressure condition on one of said surfaces to move said valve, and means to create a pressure condition on another of said surfaces to lock said valve when so moved.

12. In a fluid pressure motor, a cylinder, a piston therein, a valve having an open ended internal conduit and being provided with exterior grooves and independent surfaces facing in the same direction, inlet and exhaust connections for said cylinder for supplying and exhausting the motive fluid for oppositely facing piston surfaces, the admission connection comprising said internal conduit and the exhaust connection comprising said grooves, means responsive to motion of said piston for creating a pressure condition on one of said surfaces to move said valve, and means responsive to motion of said valve to create a pressure condition on another of said surfaces to lock said valve when so moved.

13. In a drilling machine, a drill steel, a cylinder having a piston therein for operating said steel, said valve controlling the operation of said piston, an inlet supply conduit leading to said valve, an exhaust conduit leading from said valve, conduit means leading from said exhaust conduit to the work, a throttle having inlet and exhaust conduits respectively adapted to connect with said first mentioned inlet and exhaust conduits, said conduits of said throttle being in different planes, supplementary inlet conduits in said throttle, said conduits collectively being so arranged that in one position of said valve communication between the exhaust conduits is broken and said supplementary conduits are connected to the exhaust conduit leading from the valve.

14. A hammer rock drill having, in combination, a casing provided with parallel bores, a reciprocating piston having opposed working pressure surfaces in one of said

bores, a reciprocatory tubular valve in the other of said bores, said valve having open ends in fluid communication with each other by way of the interior of said valve and being of such length that the respective ends thereof are about opposite one of said pressure surfaces of said piston when the latter is at the ends of its stroke, a passage connecting a source of pressure fluid to the bore for said valve, said passage being in permanent communication with the interior of said valve through one open end of the latter, said valve provided with separate exterior annular surfaces facing in the same direction, means including a pressure fluid conducting passage leading from one of said bores to the other for creating a pressure condition on one of said annular surfaces in response to motion of said piston for causing said valve to move and the latter to admit pressure fluid from the bore for the valve to the bore for the piston for acting upon one of said opposed pressure surfaces, said means also causing pressure fluid to act upon the other of said annular surfaces when the valve is so moved.

15. A hammer rock drill having, in combination, a casing provided with parallel bores, a reciprocatory piston having opposed working pressure surfaces in one of said bores, a reciprocatory tubular valve in the other of said bores, said valve having open ends in fluid communication with each other by way of the interior of said valve and being of such length that the respective ends thereof are about opposite one of said pressure surfaces of said piston when the latter is at the ends of its stroke, a passage connecting a source of pressure fluid to the bore for said valve, said passage being in permanent communication with the interior of said valve through one open end of the latter, said valve provided with separate exterior annular surfaces, one of said surfaces being intermediate the length of said valve and both surfaces facing in the same direction, means including a pressure fluid conducting passage leading from one of said bores to the other for creating a pressure condition on one of said annular surfaces in response to motion of said piston for causing said valve to move and the latter to admit pressure fluid from the bore for the valve to the bore for the piston for acting upon one of said opposed pressure surfaces, said means also causing pressure fluid to act upon the other of said annular surfaces when the valve is so moved.

16. A hammer rock drill having, in combination, a casing provided with parallel bores, a reciprocatory piston having opposed working pressure surfaces in one of said bores, a reciprocatory tubular valve in the other of said bores, said valve having open ends in fluid communication with each other by way of the interior of said valve and being of

such length that the respective ends thereof are about opposite one of said pressure surfaces of said piston when the latter is at the ends of its stroke, a passage connecting a source of pressure fluid to the bore for said valve, said passage being in permanent communication with the interior of said valve through one open end of the latter, said valve provided with two pairs of oppositely facing exterior annular surfaces, the surfaces of each pair facing in the same direction and one surface of each pair being intermediate the ends of the valve, means including pressure fluid conducting passages leading from one of said bores to the other for creating pressure conditions on one surface of each pair of said surfaces in response to motion of said piston for causing said valve alternately to move to opposite ends of its travel and admit pressure fluid from the bore for said valve to the bore for said piston for acting alternately upon the respective surfaces of said opposed working surface of said piston, said means also causing pressure fluid to act alternately upon the other pressure surfaces of said valve when said valve is at opposite ends of its travel.

17. A percussive tool having, in combination, a cylinder, a piston therein, a fluid-actuated, controlling valve for said piston having an internal conduit, ports and passages controlled by said valve for intermittently admitting motive fluid from said internal conduit to said cylinder for actuating said piston, a casing for said valve, said valve and casing formed to provide an expansible chamber at the exterior of said valve including a working pressure surface on said valve and an opposed working pressure surface on said casing, said valve having a passage leading from the internal conduit thereof to the exterior of the valve, said passage having a port positioned to communicate with said chamber when said valve is at one end of its travel.

18. A percussive tool having, in combination, a cylinder, a piston therein, a tubular, open-ended, fluid-actuated, controlling valve for said piston, said valve positioned parallel to said piston and having its interior in permanent communication with a source of motive fluid supply, ports and passages controlled by the end portions of said valve for alternately admitting fluid to different portions of said cylinder for reciprocating said piston, a casing for said valve, said valve and casing formed to provide a pair of expansible chambers surrounding said valve, each of which chambers includes a working pressure surface on said valve and an opposed working pressure surface on said casing, conduit means communicating with the interior of said valve providing a pair of ports on the exterior of said valve, said ports being so positioned as to cause one of them to be in

communication with one of said chambers when said valve is in one position of its travel and the other of said ports to be in communication with the other of said chambers when said valve is in another position of its travel.

5 In testimony whereof, I have signed my name to this specification.
